United States Patent Office

Des. 224,776
Patented Sept. 19, 1972

224,776

ESCUTCHEON

Raymond U. H. Tegner, Rockford, Ill., assignor to
Amerock Corporation, Rockford, Ill.

Filed Dec. 7, 1970, Ser. No. 26,331

Term of patent 14 years

Int. Cl. D8—09

U.S. Cl. D8—179

FIG. 1.

FIG. 2.

FIG. 3.

FIG. 4.

FIG. 5.

FIG. 6.

FIG. 7.

FIG. 8.

In the drawings:

FIG. 1 is a front view of an escutcheon incorporating my new design.

FIG. 2 is a side view of the escutcheon as seen from the bottom of FIG. 1.

FIG. 3 is an end view as seen from the left of FIG. 1.

FIG. 4 is an enlarged sectional view taken along the line 4—4 in FIG. 1.

FIG. 5 is a front view of a modified form of an escutcheon embodying my new design.

FIG. 6 is a side view of the escutcheon as seen from the bottom of FIG. 5.

FIG. 7 is an end view of the escutcheon as seen from the left of FIG. 5.

FIG. 8 is an enlarged sectional view taken along the line 8—8 in FIG. 5.

I claim:

The ornamental design for an escutcheon, as shown and described.
